UNITED STATES PATENT OFFICE.

GORHAM CROSBY, OF NEW YORK, N. Y.

SIGNALING SYSTEM.

1,170,613.

Specification of Letters Patent.

Patented Feb. 8, 1916.

Application filed July 12, 1910. Serial No. 571,551.

To all whom it may concern:

Be it known that I, GORHAM CROSBY, a citizen of the United States, and a resident of New York city, in the county of New York and State of New York, have invented 5 certain new and useful Improvements in Signaling Systems, of which the following is a specification.

My invention relates to improvements in 10 signaling systems designed to control the running of elevators, or similar cars, to insure their systematic operation.

One object of my invention is to provide 15 such a system in which the elevators or cars may continuously run with as little delay as possible, so that they may be substantially as systematically controlled as if controlled by a separate operator, or person usually called a starter.

20 A further object of my invention is to provide means whereby the persons operating the elevators may be suitably signaled and whereby such signals will be repeated intermittently until the signal has been 25 obeyed.

A further object of my invention is to 30 provide an arrangement which is readily adjustable to suit any number of elevators, or cars, which may be running and to suit various heights or distances to which they 35 may be designed to travel.

Further objects, features and advantages 35 will more clearly appear from the detailed description given below, taken in connection with the accompanying drawings which show diagrammatically a system embodying one form of my improvements.

In the drawings, Figure 1 is a diagram showing in a general way one form of my 40 invention. Fig. 2 is a diagram showing in detail the connections and switch arrangements in the various elevators or cars, shown in Fig. 1.

Referring to Fig. 1, A, B and C represent 45 three elevator shafts extending by the floors 1, 2, 3, 4, 5, 6, 7, 8 and 9. In the shafts A, B and C are arranged the elevators 10, 11 and 12 respectively. At the bottom of the shafts A, B and C are provided electrical 50 contact plates 13, 14 and 15, arranged to contact with the electrical contact plates 16, 17 and 18 of the elevators 10, 11 and 12 respectively, when said elevators are at the bottom of their shafts.

55 As shown in Fig. 1, the elevator 10 is at the bottom of its shaft and the contact

plates 13 and 16 are shown in electrical connection. The elevator 11 is shown part way up its shaft, while the elevator 12 is shown to be at the top of its shaft. Spaced 60 along the length of each shaft and preferably corresponding to the various floors or stations, are contact plates 19, 20, 21, 22, 23, 24 and 25 in the shaft A; contact plates 26, 27, 28, 29, 30, 31, 32, in the shaft B, and 65 contact plates 33, 34, 35, 36, 37, 38 and 39 in the shaft C. The elevator 10 is provided with a contact plate 40, arranged to contact with the contact plates 19 to 25 inclusive, as it passes up and down its shaft. 70 The elevator 11 is provided with a contact plate 41, arranged to contact with contact plates 26 to 32 inclusive, as it passes up and down its shaft. The elevator 12 is provided with a contact plate 42 arranged to 75 contact with contact plates 33 to 39 inclusive, as it passes up and down its shaft. Situated in the elevators 10, 11 and 12 are signals 43, 44 and 45 respectively. These signals may be in the form of electric bells, 80 electric lights, or other suitable forms and they are electrically connected with the contact plates 16, 17 and 18 respectively, by means of conductors 46. The other terminal of each signal 43, 44 and 45 is electrically 85 connected with ground by means of conductors 47 in any well known manner.

48 represents a storage battery or other suitable source of electrical energy, one terminal of which is connected with ground 90 by a conductor 49, which ground is the same as that to which the conductors 47 are connected. The other terminal, of the battery 48 is connected to conductors 50, 51 and 52. Conductor 50 extends into the elevator 10 95 and is arranged to be connected to the conductor 53 by means of suitable switching mechanism hereafter to be described. In a similar manner, conductor 51 extends into the elevator 11 and is arranged to be connected to the conductor 54 by similar switching mechanism. 100 In a similar manner, the conductor 52 extends into the elevator 12 and is arranged to be connected to the conductor 55 by means of similar switching 105 mechanism.

The contact plates 19 to 24 inclusive, are connected to suitable switch contacts 56, 57, 58, 59, 60 and 61 respectively, by suitable conductors as shown. The contact plate 25 110 is connected to a suitable switch member 62 by means of conductors 63 and 64. In a

similar manner the contact plates 26 to 31 inclusive, are suitably connected to switch members 65, and the contact plates 33 to 38 inclusive are suitably connected to switch members 66. Likewise, the contact plate 32 is electrically connected to switch member 67, and the contact plate 39 is electrically connected to switch member 68. Each of the contact plates, 25, 32 and 39 are also electrically connected together and with the switching members 62, 67 and 68 by means of conductors 63, 69, 70 and 71.

Assuming that the conductor 50 is connected to conductor 53; conductor 51 is connected to conductor 54 and conductor 52 is connected to conductor 55, the operation is substantially as follows: The elevator 10 being at the bottom of the shaft and the elevator 11 descending, when the elevator 11 has reached the point shown, contact plates 41 and 29 are in electrical engagement. This completes an electrical circuit through the signal 43, as follows: ground at 49, battery 48, conductor 51, conductor 54, contact plates 41, 29, corresponding switch member 65, switch member 67, conductor 70, contact plates 13, 16, conductor 46, signal 43 and conductor 47 back to ground. If the elevator or car 10 is then moved upwardly as desired, the controlling or signal circuit through signal 43 will be broken by the separation of contact plates 13 and 16. If, however, the signal should not be obeyed, then the car 11, upon further descending will cause the contact plates 41 and 30 to be brought into electrical engagement, thus repeating the signal in exactly the same manner. This repetition continues at each floor passed until the elevator 11 has reached the bottom or starting point of its line of travel. If, however, the elevator 10 starts upwardly, as desired, at the first signal, then the elevator 11, in descending and passing contact plates 30, 31 and 32 does not operate any signal because there is no car at its starting point to be signaled. Assuming that the car 10 has moved upwardly and that the car 11 has reached the bottom or starting point, then the car 12 in descending will pass the various contacts 33 to 39 inclusive. Upon reaching the contact 36 it will signal the car 11 to start upwardly, the circuits being as follows: ground 49, battery 48, conductor 52, conductor 55, contact plate 42, contact plate 36, corresponding switch member 66, switch member 68, conductor 70, contact plate 14, contact plate 17, conductor 46, signal 44 and conductor 47 back to ground. In a similar manner it will be seen that in descending or returning any elevator or car will signal any car which is at the starting point to start upwardly or along its route. If there be no car at the starting point, no such signal would be given and upon any such signal being given the signal will be

stopped upon the car moving away from the starting point.

It is desirable that the point in the descent or return of an elevator at which it will signal another car to start be adjustable, and for this purpose the various contact plates arranged along the route of each shaft are connected with the switch members 56 to 61 inclusive, 65 and 66, by throwing the switch arms 62, 67 or 68 to contact with more or less of the switch members so that the point at which a descending or returning car will give a signal may be readily adjusted. Thus, it will be seen that each of the switch members 62, 67 and 68 will place more or less of the contact plates 19 to 39 inclusive in electrical connection with the conductor 70. If it is desired that each elevator give a starting signal immediately upon its descent, the switch members 62, 67 and 68 will be thrown so as to be in electrical connection with all of the switch members 56 to 61 inclusive, 65 and 66. On the other hand, if it is desired that the descending elevators only give a signal when they are opposite the second floor, the switch members 62, 67 and 68 will be thrown so that they only contact with switch member 56 and switch members 65 and 66, which are in electrical connection with the contact plates 31 and 38 respectively.

I will now describe my improved mechanism, by which the controlling circuits in each of the cars is controlled or regulated. Referring to Fig. 2, the car 10 is shown diagrammatically on a somewhat enlarged scale, both at the bottom and at the top of the shaft A. The car 10 is provided with the usual controller 72. When the controller 72 is moved in the position shown at *l*, the car moves upwardly when the controller is near the position shown at *m*, the car is stationary and when near the position shown at *n* the car moves downwardly. The controller 72 is provided with an electrical contact plate 73, which contact plate is arranged to electrically contact with the stationary contact plate 74 when moved to the downward position. Contact plate 74 is electrically connected with the conductor 50. 75 indicates an electrical contact switch arranged to have 4 positions, as shown at *w*, *x*, *y* and *z*. Switch 75 is arranged to contact in each position with two electrical contact plates, so that in covering its four positions it will contact with eight electrical contact plates which plates are arranged in the form of a circle about the point 76, at which the switch member 75 is pivoted. 77 represents an automatic switch member pivoted at 78 and arranged to contact with the switch member 79 when properly operated. The switch member 77 has pivotally connected to it two links 80 and 81, provided with anti-friction rollers 82 and 83 at their

70

130

extremities. These friction rollers are designed to engage with cam blocks 84 and 85 at the lower and upper ends of the shaft A respectively. The cam blocks 84 and 85 are provided with cam faces 86, 87, 88 and 89, as shown. When the car 10 approaches the bottom of the shaft A, or starting point, roller 83 engages cam surface 87, thus forcing the switch member 77 about the pivot 78, so as to disengage the switch member 77 from the switch contact 79. In a similar manner, when the car 10 moves upwardly and approaches the top of the shaft A, the friction wheel 82 engages the cam surface 88, thus forcing the switch member 77 to rotate sufficiently to bring it into electrical connection with the switch contact 79. Thus, when the car moves downwardly the circuit through switch member 77 and switch contact 79 will be closed and when the car moves upwardly it will be open, as shown in the lower part of Fig. 2. If the car 10 should move farther upwardly than is shown, the switch members 77 and 79 would be again separated by the action of the roller 83 and cam surface 88, thus opening the local controlling circuit. In a similar manner, if the car 10 should pass below the position shown, the roller 82 would contact with cam surface 87 so as to electrically connect the switch members 77 and 79. It will thus appear that whenever the car passes downwardly by one or the other of the blocks 84 or 85, the switch members 77 and 79 will be connected, and when the car passes upwardly by either of said blocks, the switch members 77 and 79 will be separated. The conductor 53 is electrically connected with the switch member 77 and also with conductors 90 and 91. The switch member 79 is connected with conductors 92 and 93. The contact plate 73 is electrically connected with two of the circularly arranged contact plates of the switch 75 by means of conductors 94 and the conductor 50 is also electrically connected with two other of said switch contact plates by means of conductors 95.

With the switch member 75 in the position indicated by *w*, the local controlling conductors 50 and 53 are connected as follows: Conductor 53, switch member 77, switch member 79, conductor 92, switch member 75, conductor 94, controller contact plate 73, contact 74 and conductor 50. In this position it will therefore be seen that both the switch 77 and the controller 72 act to open the controlling circuit when the elevator or car moves upwardly and to close said circuit when it moves downwardly. This arrangement gives two switches in the circuit and is preferable. If the car was moving downwardly from the top of the shaft and before reaching the bottom desired to move upwardly again without operating the signals, this could not be done if the

switch 77 were the only one in circuit, but with the controller switch in circuit, it will be apparent that whenever the car moves upwardly the local controlling circuit will be opened thereby, so that no signal can be given when the car is moving upwardly or away from its starting point. In a similar manner, were the controller switch 72 only in circuit and the car having moved some distance upwardly then desired to return a short distance without giving any signal, this could not be accomplished; but by having the switch members 77 and 79 in circuit, it will be apparent that no signal will be given upon such short return movement, since the circuit will be broken by the switch members 77 and 79 as already described. It will therefore be apparent that where both of the switching devices 73 and 77 are in circuit, a much more satisfactory arrangement is had, since the car may move back and forth to a considerable extent between the ends of its path without giving a signal; but when it is really on its final return to the starting point, it will give the signal as desired. If, however, it is not desired to utilize the switch members 77 and 79 but only the controller switch 73, the switch member 75 will be moved to the position indicated by *x*. In this position the circuit is as follows: conductor 53, conductor 90, switch member 75, conductor 94, switch member 73, contact plate 74, to conductor 50. With this arrangement the controller 72 acts as the sole means for controlling the circuit upon each car. In case it is desired to use only the switch members 77 and 79 and eliminate the controller switch 73, the switch member 75 is moved to the position indicated by *y*, in which case the controlling circuit is as follows: conductor 53, switch member 77, switch member 79, conductor 93, switch member 75 and conductor 95 back to conductor 50. In case of the failure of both switch members 77 and 79 and the switch 73, the controlling circuit may be permanently closed as follows by putting the switch member 75 in the position indicated by *z*. In this position the local controlling circuit extends from the conductor 53 to the conductor 91, switch member 75 and conductor 95 back to the conductor 50. Under these conditions the controlling circuit may be opened by a hand switch 100.

From the above it will be apparent that I have provided an exceptionally efficient and flexible system for controlling the signalling of elevators and similar cars, in which the signalling is done automatically but substantially the same as would be done by an operator in person. The cars are under signal when at their starting point and the signal circuit is broken whenever any car departs from a starting position so that signals will not be given needlessly and con-

fusingly. By this arrangement the signals may be placed directly in the cars themselves, which could not be practically done in certain prior systems. By providing the 5 series of contact plates corresponding to the different floors or different positions along the route of travel and means whereby more or less of these may be electrically connected, the point at which a returning car will 10 give a signal may be adjusted at will to suit any number of cars in operation. Furthermore, by providing a plurality of such contact plates and having them suitably spaced, the signal is given intermittently until the 15 car signaled moves away from its starting position as desired. If, therefore, a car failed to obey the first signal the signal would be repeated substantially until obeyed. Furthermore, a car can only produce or 20 operate a signal when in some mid position. The controlling circuit in either car is broken in the car at the starting point, as will clearly appear from Fig. 1.

With my improved system any number of 25 cars can be operated thereby and parts may be so adjusted that some may be run to greater heights than others, and in this case it is only necessary to adjust the cam blocks 84 and 85 correspondingly. Even 30 with these so adjusted, the elevators or cars may run beyond them without any change being required. The cars when descending below the block 85, no matter what position it occupies, will, nevertheless, properly operate 35 the signals when it passes below this block in its return passage.

Although I have described my improvements with respect to a particular embodiment thereof and have shown the system 40 diagrammatically in the drawings, nevertheless it will be apparent that many changes may readily be made well within the spirit and scope of my invention. For instance, the contact plates 19 to 39 inclusive might 45 be arranged similarly on an independent switchboard, provided with switching members for traveling thereover corresponding to the contacts 16 to 18 and 40 to 42 inclusive, which contacts would be operated by 50 the elevators or cars through any suitable mechanism. In a similar manner the switching devices shown in Fig. 2 may be modified to a large extent without departing from the spirit and scope of my invention. 55 However, having fully and clearly described my improvements, what I claim as new and desire to secure by Letters Patent of the United States, is:

1. The combination of a plurality of 60 traveling cars, each having a starting position, starting signaling means for said cars, means operated by the movement of a car on its return toward its starting position but not by the movement of the car away 65 from the starting position for causing the

operation of the signaling means for any car at its starting position, and means for adjusting the point at which the returning car causes the operation of said signaling means.

2. The combination of a plurality of traveling cars, each having a starting position, starting signaling means for said cars, means controlled by the movement of a car on its return toward its starting position for 70 causing the starting of the operation of the signaling means for another car, and means for adjusting the point at which the returning car starts the operation of said signaling means on another car.

3. The combination of a plurality of traveling cars each having a starting position, starting signaling means for said cars, and means controlled by a car at successive 80 points on its return toward its starting position, for causing the operation of the signaling means for another car, and causing the intermittent repeating of the signal as the returning car continues toward its starting position, the signaling means for a car 90 being inoperative when the car is away from its starting position.

4. The combination of a plurality of traveling cars each having a starting position, starting signaling means for said cars, 95 and means controlled by the movement of any car toward its starting position but not by the movement of the car away from the starting position for causing the operation of the signaling means for any car at its 100 starting position, the signaling means being inoperative for any car when it is not at its starting position.

5. The combination of a plurality of traveling cars each having a starting position, starting signaling means for said cars, means controlled by a car at successive 105 points on its return toward its starting position but not on its movement away from its starting position for causing the operation of the signaling means for another car, and causing the intermittent repeating of the signal as the returning car continues 110 toward its starting position.

6. The combination of three or more traveling cars each having a starting position, a starting signal carried by each of 115 said cars, means controlled by the movement of any car only toward its starting position for causing the operation of the signal 120 for any car at its starting position, the signal being inoperative for any car when it is not at its starting position.

7. The combination of a plurality of traveling cars each having a starting position, starting signaling means for said cars, means controlled by a car at successive 125 points for starting the operation of the signaling means for another car and causing the intermittent repeating of the signal as 130

the car continues toward its starting position.

8. The combination of a plurality of traveling cars, each having a starting position, starting signaling means for said cars, means controlled by the movement of a car for causing the operation of the signaling means for any car at its starting position, and means for adjusting the point at which 10 the car causes the operation of said signaling means of another car to start the latter.

9. The combination of a plurality of traveling cars each having a starting position, means for controlling the movement of 15 each car, starting signaling means for said cars, and means controlled by the movement of a car for causing the operation of the signaling means for another car, said controlling means being operatively related to said 20 last mentioned means whereby when the controlling means is operated to move a car away from the starting position said last mentioned means on the car is rendered inoperative to cause the operation of the signaling means for any car, said means controlled by the movement of a car embracing 25 an electrical controlling circuit for a car, switching means operated by the movement of each car and switching means operated 30 by the controller of each car.

10. The combination of a plurality of traveling cars each having a starting position, a signaling means carried by each of said cars, and switching means for each car 35 controlled by the movement of the car toward its starting position for causing the operation of the signaling means for any car at its starting position, said switching means for each car when the car is at its 40 starting position, being inoperative to cause the operation of the signaling means for any car.

11. The combination of a plurality of traveling cars each having a starting position, starting signaling means for said cars, means for each car controlled by the movement of the car for causing the operation of the signaling means for any car at its starting position, and electrical switching means 50 controlled by the movement of the car for rendering said controlled means, when its car is moving away from its starting position, inoperative to cause the operation of said signaling means for any car, means for controlling the movement of each car, and means controlled by said last mentioned means, for rendering said first mentioned controlled means, when its car is moving away from its starting position, inoperative 55 to cause the operation of said signaling means for any car.

12. The combination of a plurality of traveling cars each having a starting position, starting signaling means for said cars, an electrical circuit for controlling the op- 60

eration of the signaling means for each car, electrical switching means for each car controlled by the movement of the car for causing the operation of the signaling means for any car at its starting position, and a second 70 electrical switching means controlled by the movement of the car for rendering the first mentioned switching means, when its car is moving away from its starting position, inoperative to cause the operation of said 75 signaling means for any car, a controller for each car, switching means on each car controlled by the controller, for rendering said first mentioned switching means, when its car is moving away from its starting position, inoperative to cause the operation of 80 said signaling means for any car.

13. The combination of a plurality of traveling cars each having a starting position, starting signaling means for said cars, 85 an electrical circuit for controlling the operation of the signaling means for each car, electrical switching means for each car controlled by the movement of the car for causing the operation of the signaling means for 90 any car at its starting position, and a second electrical switching means controlled by the movement of the car for rendering the first mentioned switching means, when its car is moving away from its starting position, inoperative to cause the operation of said 95 signaling means for any car, a controller for each car, switching means on each car controlled by the controller, for rendering said first mentioned switching means, when its car is moving away from its starting position, inoperative to cause the operation of said signaling means for any car, and means whereby either or both of said second and third mentioned switching means may be 100 thrown out of operation.

14. The combination of a plurality of traveling cars each having a starting position, electric signaling means for said cars, said signaling means being inoperative for 110 any car while away from its starting position, switching means controlled by the movement of any car returning to its starting position for causing the operation of the signaling means for any car at its start- 115 ing position, and switching means automatically controlled for preventing said first mentioned switching means from causing the operation of the signaling means when its car is moving away from its starting po- 120 sition.

15. The combination of a plurality of traveling cars each having a starting position, electric signaling means for said cars, said signaling means being inoperative for 125 any car while away from its starting position, switching means controlled by the movement of any car returning to its start- 130 ing position for causing the operation of the signaling means for any car at its

starting position, and switching means automatically controlled for preventing said first mentioned switching means from causing the operation of the signaling means when its car is moving away from its starting position, said first mentioned switching means having a plurality of contacts for causing the intermittent repeating of the signaling means.

10 16. The combination of a plurality of traveling cars each having a starting position, electric signaling means for said cars, said signaling means being inoperative for any car while away from its starting position, switching means controlled by the movement of any car returning to its starting position for causing the operation of the signaling means for any car at its starting position, and switching means automatically controlled for preventing said first mentioned switching means from causing the operation of the signaling means when its car is moving away from its starting position, and means for adjusting the point at which a returning car causes the operation of said signaling means.

17. The combination of a plurality of traveling cars, each having a starting position, electric signaling means for said cars, said signaling means being inoperative for any car while away from its starting position, switching means controlled by the movement of any car returning to its starting position for causing the operation of the signaling means for any car at its starting position, and switching means automatically controlled for preventing said first mentioned switching means from causing the operation of the signaling means when its car is moving away from its starting position, and means for adjusting the point at which a returning car causes the operation of said signaling means, said first mentioned switching means having a plurality of contacts for causing the intermittent repeating of the signaling means.

18. The combination of a plurality of traveling cars each having a starting position, electric signaling means for said cars, said signaling means being inoperative for any car while away from its starting position, switching means controlled by the movement of any car returning to its starting position for causing the operation of the signaling means for any car at its starting position, and switching means automatically controlled for preventing said first mentioned switching means from causing the operation of the signaling means when its car is moving away from its starting position, and a controller for controlling the movement of each car, said last mentioned switching means being controlled by the controller of its car.

65 19. The combination of three or more

traveling cars each having a starting position, an electric signaling means carried by each of said cars, said signaling means being inoperative for any car while away from its starting position, switching means controlled by the movement of any car returning to its starting position for causing the operation of the signaling means for any car at its starting position, and switching means automatically controlled for preventing said first mentioned switching means from causing the operation of the signaling means when its car is moving away from its starting position, said first mentioned switching means having a plurality of contacts for causing the intermittent repeating of the signaling means, and means for adjusting the point at which a returning car starts the operation of said signaling means, and a controller for controlling the movement of each car, said last mentioned switching means being controlled by the controller of its car.

20. The combination of a plurality of traveling cars each having a starting position, an electric signal for each car, the signal for any car being inoperative when the car is away from its starting position, switching means operated by the movement on its return to its starting position for causing the operation of the signal of any car at its starting position, and switching means automatically controlled for preventing a car, when moving away from its starting position, from causing the operation of the signal of any car at the starting position.

21. The combination of a plurality of traveling cars each having a starting position, signaling means for said cars comprising an electrical circuit for each car, switching means for closing the circuit of a car at one point when the car is at its starting position, and opening the circuit at said point when the car is at other positions, switching means for closing the circuit of a car at another point and controlled by another car when it is returning to its starting position, and switching means for automatically opening the circuit at another point when said other car is moving away from its starting position.

22. In a signaling system, a plurality of traveling cars, each having a starting position, a starting signal for each car, and means operated by a car returning to its starting position for operating the starting signal for any car at its starting position and for repeating said signal only while the car is returning to its starting position, and the car at its starting position remains at its starting position.

23. In a signaling system, a plurality of traveling cars, each having a starting position, starting signaling means for said cars, and means operated by a car returning to

its starting position for operating the starting signal for any car at its starting position and for repeating said signal, only while the car at its starting position remains 5 at its starting position.

24. In a signaling system, a plurality of traveling cars, each having a starting position, starting signaling means for said cars, and means operated at successive points by 10 a car returning to its starting position for operating the starting signal for any car at its starting position and for repeating said signal while the car is returning to its starting position.

25. In a signaling system, a plurality of traveling cars, each having a starting position, starting signaling means for said cars, and means operated by a car returning to its starting position for operating the starting signal for any car at its starting position and for repeating said signal only while the car is returning to its starting position.

26. In a signaling system, a plurality of traveling cars, each having a starting position, a starting signal carried by each car, means operated at successive points by a car returning to its starting position for intermittently operating the signal of any car at its starting position, the signal of each car being inoperative when the car moves away 20 from its starting position.

27. In a signaling system, a plurality of traveling cars, each having a starting position, starting signaling means for said cars, and means only controlled by any car returning to its starting position for operating said signaling means for starting any car at its starting position and for continuing the operation of said signaling means only until 35 said returning car substantially reaches its starting position.

28. In a signaling system, a plurality of traveling cars, each having a starting position, starting signaling means for said cars, and means controlled by any car returning to its starting position for operating said signaling means for starting any car at its starting position and for continuing the operation of said signaling means until said 45 returning car substantially reaches its starting position, the signaling means being inoperative for any car when it moves away from its starting position.

29. In a signaling system, a plurality of traveling cars, starting signaling means for said cars, and means whereby each car during a material portion of its descent will cause the actuation of the signal for any car at one end of its line of travel, said 55 means being arranged to operate said signal only until the car signaled has started upwardly.

30. In a signaling system, a plurality of traveling cars, each having a starting position, a starting signal for each car and 60

means controlled by a car at successive points while the car is returning to the starting position for causing the operation of the starting signal for any car at the starting position and repeat said signal until the returning car has substantially reached its starting position, or until the car at the starting position moves away therefrom. 70

31. The combination of a plurality of traveling cars, signaling means for said cars, and means controlled by the movement of any car at successive points for causing the intermittently repeated operation of the signaling means for another car until the latter car obeys the signaling. 75

32. The combination of a plurality of traveling cars, signaling means for said cars, means controlled by the movement of any car for causing the operation of the signaling means for another car, and electrical switching means for adjusting the point in 80 its travel at which said first mentioned car starts the operation of the signaling means.

33. In a signaling system, the combination of a plurality of traveling cars, each having a starting position, a starting signal for each car, an electric signal circuit for each signal, means whereby each signal circuit is closed at one point when the car is at its starting position, means whereby each signal circuit 90 is closed at a plurality of points by the return travel of a car to its starting position, each signaling circuit being open while its car is moving away from its starting position due to the movement of the car, and 100 means for varying the point at which the signaling circuit is closed by the return of a car to the starting position.

34. In a signaling system, the combination of a plurality of traveling cars, each having a starting position, a starting signal for each car, an electric signal circuit for each car arranged to be opened and closed by the movement of the same, and switch means actuated by the movement of the car for 105 causing the circuit to be open during travel away from the starting position and closed during travel toward the starting position, a controller for each car, and a switch actuated by the controller for causing the controlling circuit to be open at one point during 110 travel away from the starting position and closed at that point during travel toward the starting position.

35. In a signaling system, the combination 120 of a plurality of traveling cars, each having a starting position, a starting signal for each car, an electric signal circuit for each car arranged to be opened and closed by the movement of the same, and a switch actuated by the movement of the car for causing the circuit to be open during travel away 125 from the starting position and closed during travel toward the starting position, a controller for each car, and a switch actuated 130

by the controller for causing the circuit to be open during travel away from the starting position and closed during travel toward the starting position, and means 5 whereby either or both of said switches may be thrown into operative relation with the controlling circuit singly or simultaneously.

36. The combination of a plurality of traveling cars, signaling means for said cars, 10 means controlled by the movement of any car for causing the operation of the signaling means for another car, a controller for each car, and means controlled by the controller for preventing its car from causing 15 the operation of the signaling means during certain stages of the operation.

37. In a signaling system, the combination of a plurality of traveling cars, each having a starting position, a starting signal for each 20 car, a controlling circuit for each car to control the operation of the signals, a controller for regulating the operation of each car and means whereby said circuit is controlled by 25 said controller.

38. In a signaling system, the combination of a plurality of traveling cars, each having a starting position, a starting signal for each car, a controlling circuit for each car for controlling the operation of the signals, 30 means whereby only a return movement of the car regulates the action of said circuit to operate the signals and a hand switch on each car for opening or closing said controlling circuit for another car.

39. The combination of a plurality of traveling cars, signaling means for said cars, means controlled only by a return movement of any car for causing the operation 40 of the signaling means for another car, and a hand operated means in each for preventing it from causing the operation of said 45 signaling means.

40. In a signaling system, the combination of a plurality of traveling cars, each having a starting position, a starting signal for each car, and means whereby a car returning to 50 its starting position will start the operation of the starting signal of any car at its starting position, at a predetermined point in the travel of the returning car and cause the operation of said starting signal during further travel of the car to its starting position.

41. In a signaling system, the combination of a plurality of traveling cars, each having a starting position, a starting signal for each car and means whereby a car returning to its starting position will cause the operation of the starting signal of any car at its starting 55 position, at a predetermined point in the

travel of the returning car and intermittently cause the operation of said starting signal during further travel of the car to its starting position and means whereby said predetermined point may be adjusted to suit 65 the number of cars in service.

42. In a signaling system, the combination of a plurality of traveling cars, each having a starting position, a starting signal for each car, and means whereby a car returning to its starting position will cause the operation of the starting signal of any car at its starting position, at a predetermined point in the travel of the returning car and means whereby said predetermined point may be adjusted 70 to correspond to any floor or station at which the cars are designed to stop.

43. In a signaling system, a plurality of traveling cars, each having a starting position, a starting signal for each car and means 80 whereby a car returning to the starting position will cause the operation of the starting signal for any car at the starting position and repeat said signal until the returning car has substantially reached its starting 85 position and means whereby said predetermined point may be adjusted to correspond to any floor or station at which the cars are designed to stop.

44. The combination of a plurality of traveling cars each having a starting position, starting signaling means for said cars, means controlled by the movement of any car toward its starting position but not by the movement of the car away from its starting 90 position for causing the operation of the signaling means for any car at its starting position, the signaling means being inoperative for any car when it is not at its starting position, and means for adjusting the point 95 at which the returning car causes the operation 100 of the signaling means.

45. The combination of a plurality of traveling cars each having a starting position, starting signaling means for said cars, 105 means controlled by the movement of a car on its return toward its starting position for causing the operation of the signaling means for another car, and electrical switching means external to and independent of the 110 car for adjusting the point at which the returning car causes the operation of said signaling means.

Signed at New York city, in the county of New York and State of New York this 115 11th day of July, A. D. 1910.

GORHAM CROSBY.
